UNITED STATES PATENT OFFICE.

ALFRED B. DAVIS, OF PHILADELPHIA, PENNSYLVANIA, ASSIGNOR, BY MESNE ASSIGNMENTS, OF ONE-HALF TO ERNEST H. CHASE, OF PHILADELPHIA, PENNSYLVANIA.

FOUNTAIN-PEN.

SPECIFICATION forming part of Letters Patent No. 766,760, dated August 2, 1904.

Application filed February 2, 1904. Serial No. 191,702. (No model.)

To all whom it may concern:

Be it known that I, ALFRED B. DAVIS, a citizen of the United States, residing in Philadelphia, Pennsylvania, have invented certain Improvements in Fountain-Pens, of which the following is a specification.

My invention consists of an improved fountain-pen of the class provided with filling-pistons, the object of the invention being to provide a pen of the class noted which shall be of simple and inexpensive construction and efficient in operation.

It is further desired to provide a pen of such construction that it will not be liable to get out of order or to become inoperative by reason of the thickening of the ink used and one that can be cleaned by drawing in and ejecting water without removing the pen or feeder.

Another object of the invention is to provide a fountain-pen having a feeder of improved construction.

These objects I attain as hereinafter set forth, reference being had to the accompanying drawings, in which—

Figure 1 is a sectional elevation of my improved pen, showing the detail construction of its parts. Fig. 2 is a side elevation of my improved feeder. Figs. 3 and 4 are respectively a plan view and an end elevation of the feeder shown in Figs. 1 and 2, and Fig. 5 is an enlarged sectional elevation showing the detail construction of a part of my invention.

In the above drawings, A is a tubular section, usually formed of hard rubber or other suitable material and closed at one end. Entering the open end of said section is a body or pen-carrying section B, which is also tubular and open at that end which enters the said body portion. In its opposite end is fitted a piece C, which serves the double function of plug for said end and feeder for a pen c, which is confined between it and the end of the said section B. The open end of the section A is provided with an inwardly-extending flange a, while the adjacent end b' of the body-section B is enlarged and provided with annular grooves b, which are preferably filled

with some form of material, such as a solid lubricant or body of packing. This construction of the parts A and B prevents the withdrawal of one from the other.

The feeder C is of such a cross-section that it closes the end of the body-section B, with the exception of two relatively contracted openings on each side of its central longitudinal rib c'. This rib engages the under side of and extends parallel with the pen c, and the body of the feeder C is so cut away as to form the above-mentioned openings, which increase in area of cross-section from the point of the pen inwardly. It will thus be seen that ink flowing to the pen passes out through channels formed on either side of the rib c' of the feeder and is directed in two streams to the under side and point of the pen. Said feeder is preferably made of soft rubber, since this is the only material which can be used to close the end of the tubular section with sufficient tightness without pressing so hard on the pen as to spread the nibs thereof. Furthermore, by reason of the material of the feeder following the nibs of the pen as they are bent in the action of writing there is caused a pumping action which insures a constant flow of ink to the pen.

When it is desired to fill the device with ink, the section A and the body-section B are first collapsed or pushed together as far as possible, after which the pen is inserted in a reservoir containing ink, and the body portion is slowly pulled out of the pen-carrying section. This action causes ink to be drawn into the interior of the pen, after which said pen is ready for use.

When it is desired to clean the device, the pen and feeder can be pulled out of the body-section B, thus giving access to the interior of the pen and permitting quick removal of any hard or gummy material which may have collected, or, if desired, water can be drawn in and ejected to cleanse the feed and pen.

In Fig. 1 I have shown in dotted lines a cap or cover D, which is of length sufficient to fit over the body-section and to frictionally engage the end of the section A even when said

section B is in its fully-extended position. When the pen is in use, this cap fits over and frictionally engages the rear of the section A, it being understood that this latter is suitably 5 adapted for the reception of said cap.

I claim as my invention—

1. A fountain-pen having a tubular section, a pen in the end thereof and a feeder of relatively resilient material for said pen, said 10 feeder being of a substantially circular section and having longitudinal grooves on either side of it, substantially as described.
2. The combination in a fountain-pen of a tubular section having a pen, a feeder therefor 15 of soft, relatively elastic material fitting into the front end of said tubular section, said feeder being grooved longitudinally so as to form a rib, said rib being in contact with under side of the pen, substantially as described.
3. The combination in a fountain-pen of a tubular section having in one end a pen with a feeder therefor, the feeder having grooves decreasing in area of cross-section as they approach the point of the pen, said feeder otherwise filling the end of the tube, substantially 25 as described.
4. The combination of a tubular section having in one end a pen and a feeder of soft, relatively elastic material, there being grooves in 30 said feeder extending adjacent to the pen, and

so placed as to form a rib in contact with the under side of the pen, substantially as described.

5. The combination in a fountain-pen of a tubular section having in one end a metallic 35 pen and a feeder therefor of soft rubber, said feeder having longitudinal grooves placed to form a rib, said rib being in contact with the under side of the pen, substantially as described.

6. The combination in a fountain-pen of a tubular reservoir having in one end an opening, a pen and a feeder in said opening, said feeder having a longitudinally-extending rib portion in contact with the pen, there being 45 a channel in the feeder on each side of said rib, substantially as described.

7. The combination with a tubular reservoir of a pen and a feeder therefor of compressible material, there being a conduit for 50 ink in said feeder, the same being placed to deliver ink to the under side of the pen, substantially as described.

In testimony whereof I have signed my name to this specification in the presence of two subscribing witnesses. 55

ALFRED B. DAVIS.
